UNITED STATES PATENT OFFICE.

BERTRAM A. SEGAR, OF NEW YORK, N. Y., ASSIGNOR TO THE SEGAR STUDIOS INC., A CORPORATION OF NEW YORK.

DESIGN FOR A STRIP OR BANDING FOR DECORATIVE PURPOSES.

Application filed July 14, 1924. Serial No. 10,146. Term of patent 7 years.

To all whom it may concern:

Be it known that I, BERTRAM A. SEGAR, a subject of the King of Great Britain, and a resident of the city, county, and State of New York, have invented a new, original, and ornamental Design for Strip or Banding for Decorative Purposes, of which the following is a specification, reference being had to the accompanying drawing, forming a part hereof.

In these drawings:

Fig. 1 is a front elevational view of the strip or banding for decorative purposes.

Fig. 2 is a side elevation of the strip or banding for decorative purposes.

I claim:

The ornamental design for a strip or banding for decorative purposes substantially as shown.

BERTRAM A. SEGAR.
